UNITED STATES PATENT OFFICE

2,184,863

MECHANICAL PENCIL

Lucifer J. Most, Hudson County, N. J.

Application April 5, 1939, Serial No. 266,055

2 Claims. (Cl. 120—18)

My invention relates to a mechanical pencil of the type described in my pending application, Serial Number 208,739, filed May 19, 1938.

The object of the invention is to provide a simple mechanism, formed of few moving parts, for propelling, repelling, expelling and automatically presenting a new lead to writing position.

Another object of the invention is to provide a mechanical pencil in which the lead itself is part of the feed mechanism.

A further object of the invention is to provide a feeding means which engage a portion of the lateral surface of the lead when feeding it.

In the appended drawing, forming part of this application, Figure 1 is a vertical fragmentary section of a pencil embodying my invention. The leads are removed to better illustrate the invention.

Figure 2 is an enlarged end elevation of Figure 20 1, with the eraser removed.

Figure 3 is an enlarged cross-section on line 3—3, Figure 1 with the lead shown in section, and Figure 4 is an elevation of a combination gear and worm.

Referring to the drawing, 10 is the pencil barrel, terminating with a tip 11, having a lead outlet 12. Mounted within the tip, in alignment with the opening 12, is a lead guide 13 of round tubular cross-section. The lower end of the guide 15 is held firmly at the tip opening 12, while the upper end of said guide 13 passes through a washer 14, set firmly in the barrel at the tip. The upper end of the guide terminates with a hopper 15, positioned within the lower end of a tube 16, revolvably mounted within the barrel 10. The upper end of said tube 16 projects above the upper end of the barrel, and thereat accommodates an eraser 17. The tube 16 with hopper 15 therein constitutes the magazine of the barrel.

The lower end of the tube 16 bears on the washer 14, and thereat the tube 16 is provided with teeth to form internal gear 18. In mesh with the internal gear 18 are gears or pinions 19

revolvably mounted between the washer 14 and a washer 20, fixed to the guide 13 below the hopper 15. The two washers housing the corresponding shafts 21 on which the spur gears 19 revolve.

The guide 13 is apertured peripherally to permit the gears 19 to pass into the passage for the lead in the guide 13. The peripheral surfaces of the spur gears 19 are provided with spiral grooves, transforming the gears into worms, which, when engaging the lateral surface of a lead passing the 10 guide, will move it longitudinally in either direction, depending on the direction the worms are rotated through the medium of the tube 10.

Although the drawing and the description refers to a pair of spur gears diametrically opposite, three gears may be used for better engagement, or a single one may be used to advantage, particularly if a lead of angular cross-section is used in lieu of a round one described.

I claim:

1. In a mechanical pencil, a barrel having a tip forming a lead outlet, a lead guide of tubular cross-section in the tip merging with the lead outlet thereof, a hopper above the guide in the barrel, a tube revolvably mounted in the barrel 25 and housing the hopper and forming therewith a magazine for leads, an internal gear associated with the tubular member and constrained to revolve therewith, and a spur gear in mesh with the internal gear to be revolved by said internal 30 gear, said spur gear having spiral grooves on its toothed periphery, said guide having an opening on the side thereof for admitting the spur gear into the passage substantially by the depth of its spiral grooves, to engage a lead positioned 35 in the guide.

2. In a mechanical pencil, a barrel having a lead guide, a spur gear provided with spiral grooves on its toothed periphery entering the guide from the lateral surface thereof through the depth of the spiral grooves, and means for turning the spur gear from the end of the barrel. 40

LUCIFER J. MOST.
